ENGINE STARTER GEARING

James E. Buxton, Frank T. Christian, and Rene E. Demure, Elmira, N. Y., assignors to Bendix Aviation Corporation, a corporation of Delaware

Application May 27, 1947, Serial No. 750,726

3 Claims. (Cl. 74—7)

1

The present invention relates to engine starter gearing and more particularly to a starter drive of the type in which a pinion is automatically traversed into and out of mesh with a gear of an engine to be started.

Engine starter drives as now commercially manufactured are generally of the so-called "barrel" type in which a smooth-bored drive pinion is slidably journaled on the motor shaft for longitudinal movement into and out of mesh with an engine gear, and is actuated by a control nut threaded on a motor driven screw shaft, the pinion being connected to the control nut by a hollow barrel member.

In order to secure reliable traversing action of the nut under all conditions of congealed lubricant etc., it is necessary that the inertia of the nut, barrel and pinion as respects rotation be large relatively to the inertia of these parts in respect to longitudinal movement. This result may readily be secured by increasing the diameter of the barrel while preferably reducing its wall thickness, but when this practice is followed too far, undesired reengagements of the pinion with the engine gear after demesh are encountered. These undesired reengagements are caused by the fact that the operator does not ordinarily open the starting switch at the instant the engine fires and demeshes the pinion. The starting motor therefore accelerates due to the release of the cranking load thereon and consequently traverses the control nut, barrel and pinion back toward the engine fly wheel until the pinion strikes the side of the rapidly rotating engine gear, causing unnecessary wear and noise.

It is an object of the present invention to provide a novel engine starter drive having adequate rotational inertia to secure traversal under adverse circumstances, but having means for preventing traversal of the pinion back toward the engine gear after being demeshed therefrom.

It is another object to provide such a device in which the pinion is free to traverse readily into mesh with the engine gear when it is not rotating, but including means for resisting such traversal when the pinion and its associated parts are in rotation.

Further objects and advantages will be apparent from the following description taken in connection with the accompanying drawing, in which:

Fig. 1 is a side elevation partly broken away and in section of a preferred embodiment of the invention;

2

Fig. 2 is a section taken substantially on the line 2—2 of Fig. 1.

Fig. 3 is a detail in perspective, partly broken away and in section, of the barrel and pinion assembly; and

Fig. 4 is a view similar to Fig. 2 of a modified form of the invention.

In Fig. 1 of the drawing, there is illustrated a power shaft 1 which may be the extended armature shaft of a starting motor not illustrated, the outer end of which is supported in an outboard bearing 2 preferably attached to the frame of the starting motor. A pinion 3 is slidably journaled on the power shaft for longitudinal movement into and out of mesh with a gear 4 of the engine to be started. A hollow sleeve 5 is fixed on the power shaft 1 as by means of a pin 6 and is yieldably connected by means of a drive spring 7 to a screw shaft 8 which is slidably journaled on a reduced portion 9 of said sleeve, the screw shaft being retained on the sleeve by a stop nut 11.

A control nut 12 is threaded on the screw shaft 8 and is rigidly connected as indicated at 13 to a cylindrical barrel 14 which is rigidly attached to the pinion 3 as shown at 15.

The threads of the screw shaft 8 terminate adjacent the idle position of the control nut 12 leaving a smooth portion 16 on which the control nut is free to rotate when the pinion and barrel assembly overruns the screw shaft, and a light compression anti-drift spring 17 bearing on the control nut 12 and stop nut 11 urges the stop nut toward idle position. Means for causing the control nut to enter upon the threads of the screw shaft so as to be traversed to the right upon acceleration of the screw shaft is provided in the form of a re-entry spring 18 located in the inner end of the barrel 14 and bearing against a thimble 19 which normally rests against the stop nut 11.

Means for limiting the expansion of the re-entry spring 18 is provided in the form of a lock ring 21 seated in a groove in the interior of the barrel in position to engage the peripheral flange 22 of the thimble 19 so as to maintain the re-entry spring under initial compression.

In order to increase the rotational inertia of the pinion and barrel assembly, a hollow cylindrical inertia member 23 of considerably greater diameter than the barrel is rigidly mounted on the exterior thereof. This inertia member is also utilized to prevent undesired traversal of the pinion and barrel assembly toward the engine gear when the parts are rotating. This function is accomplished by mounting the inertia member eccentrically with respect to the barrel so that

rotation thereof around the axis of the barrel causes a radial thrust to be applied to the control nut 12 thereby developing a frictional gripping effect of the control nut on the threads of the screw shaft.

As best shown in Figs. 2 and 3, the rigid attachment of inertia member 23 to the barrel 14 is preferably brought about by forming depressions or dimples 26 in the inertia member at substantially diametrical positions in relation to the barrel and arranged to closely engage the barrel, while the intermediate portion of the inertia member 23 is fixed to the barrel by welding or brazing as indicated at 25 so as to form a rigid permanent connection.

In the operation of this drive, starting with the parts in the positions illustrated in Fig. 1, rotation of the power shaft 1 in the direction of the arrow is transmitted to the screw shaft 8, causing the control nut 12 to be traversed to the right along the screw shaft until the pinion 3 is fully meshed with the engine gear 4, at which time the control nut 12 engages the stop nut 11 whereupon the pinion 3 is constrained to rotate with the screw shaft to crank the engine. During this traversal, the inertia member 23 by virtue of its large diameter and comparatively thin wall, greatly increases the rotational inertia of the pinion and barrel assembly relative to its inertia as respects longitudinal movement so as to insure traversal of the pinion into mesh under the most adverse conditions.

When the engine fires, the acceleration of the engine gear 4 is transmitted to the pinion 3, causing the pinion and barrel assembly to overrun the screw shaft 8 whereby the control nut 12 is threaded back along the screw shaft until it runs off the ends of the threads thereon. Since the pinion 3 is thus demeshed from the engine gear 4, the pinion and barrel assembly quickly decelerates to the speed of the screw shaft, whereupon the re-entry spring 18 becomes effective to re-engage the control nut 12 with the ends of the threads on the screw shaft 8. It will be understood that this demeshing action normally takes place in a fraction of a second so that the screw shaft and motor shaft are still rotating substantially at cranking speed.

If, under these circumstances the operator fails to open the starting switch so as to deenergize the starting motor, the power shaft 1 and screw shaft 8 will be rapidly accelerated by the release of the cranking load therefrom, and this acceleration will tend to traverse the control nut and the pinion and barrel assembly toward the engine gear. At this time, however, the pinion and barrel assembly including the inertia member 23 are in rotation, and the eccentricity of the inertia member 23 causes it to press the control nut 12 against the threads of the screw shaft on the side to which the eccentric inertia member is attached. The eccentricity of the inertia member is so related to the rotational moment of inertia of the pinion and barrel assembly and the acceleration characteristics of the starting motor that adequate lateral pressure is brought to bear

on the control nut to prevent such undesired translation of the pinion and barrel assembly, whereby the parts merely spin idly together until the operator opens the starting switch.

Fig. 4 illustrates a modification of the invention in which the eccentric weighting of the barrel member is obtained by forming the eccentric cylindrical member integral with the barrel itself. As there shown, the interior cylindrical surface 26 of the barrel 14' is coaxial with the screw shaft 8 as in the first embodiment of the invention, but the exterior cylindrical surface 27 of the barrel is abaxial thereto so as to weight the barrel eccentrically.

Rotation of the barrel will cause centrifugal force to apply radial pressure from the barrel to the nut to increase the friction of the nut on the screw shaft, and thereby oppose relative rotation therebetween the same as in the first embodiment of the invention.

Although but two embodiments of the invention have been shown and described in detail, it will be understood that other embodiments are possible and that changes may be made in the proportions and arrangement of the parts without departing from the spirit of the invention as defined in the claims appended hereto.

What is claimed is:

1. In an engine starter drive, a power shaft, a pinion slidably journaled thereon for movement into and out of mesh with a gear of an engine to be started, a screw shaft, means connecting the screw shaft to rotate with the motor shaft, a control nut threaded on the screw shaft, a barrel member connecting the control nut and pinion, a hollow cylindrical inertia member, and means for connecting the inertia member to rotate with the barrel member while maintaining the inertia member eccentric thereto.

2. An engine starter drive as set forth in claim 1 in which said inertia member is in the form of a cylinder having an internal diameter substantially greater than the outside diameter of the barrel, and rigidly fixed thereto on one side.

3. An engine starter drive as set forth in claim 1 in which said inertia member is in the form of a cylinder having an internal diameter substantially greater than the outside diameter of the barrel, and rigidly fixed thereto on one side, said cylinder having inwardly protruding means for engaging the exterior of the barrel at points circumferentially spaced from its attachment thereto so as to prevent lateral movement of the cylinder on the barrel.
